UNITED STATES PATENT OFFICE.

THOMAS OWEN ARNFIELD AND WILLIAM BOOTH, OF NEW MILLS, ENGLAND.

BEETLING-MACHINE.

1,090,590.

Specification of Letters Patent.

Patented Mar. 17, 1914.

Application filed December 5, 1913. Serial No. 804,848.

To all whom it may concern:

Be it known that we, THOMAS OWEN ARNFIELD and WILLIAM BOOTH, subjects of the King of Great Britain and Ireland, residing, respectively, at Globe Ironworks, New Mills, in the county of Derby, England, and 44 Hall street, New Mills aforesaid, have invented new and useful Improvements in or 10 Connected with Beetling-Machines, of which the following is a specification.

Our said invention relates to improvements in or connected with pneumatic beetling machines, that is, to beetles wherein the hammers are separately or otherwise actuated by air pressure.

It has been proposed in beetles, to utilize a series of air cylinders in which pistons have been fitted, each of such cylinders being connected by a passage to another cylinder in which another piston moved, each of such other pistons carrying a hammer or beetling block. This arrangement is however a somewhat complicated and expensive construction and the incidental combination 25 of mechanism following upon such arrangement has required very considerable power to drive and entailed much friction and wear and tear. It has also been proposed to utilize a fixed cylinder within which two pistons move one connected to the beetling hammer and the other actuated by a crank, eccentric or the like and in such suction is presumed to lift the hammer away from the cloth beam while gravity accentuated by air 30 pressure due to one piston overtaking the other forces the hammer downward onto the cloth beam to strike the blow.

Now our invention consists in the employment of a sliding or movable outside cylinder in connection with each beetle head and which sliding or movable outside cylinder is directly or indirectly actuated by an eccentric cam or such like. The hammer acts upward on the cloth beam, and, on the descent of the sliding outside cylinder, the hammer falls away from the beam by gravity assisted by suction. Likewise the sliding outside cylinder is also charged with air which on the return stroke is compressed and forces the hammer onto the beam. The result of such an arrangement is, that as against the one system the cost of working is greatly diminished and we are enabled to dispense with a separate cylinder and separate piston and indirect actuation, and, at the same time to do away with eccentric clips, eccen-

tric rods, pins, &c., and to eliminate a great deal of friction and to do away with parts liable to break or cause strain. As against the other system our improved method represents a more positive and efficient arrangement according to which gravity aided by suction insures the hammer falling during descent of the sliding outside cylinder and compressed air forces the hammer upward onto the beam.

We employ a combined pneumatic hammer head and outside sliding cylinder and we actuate such sliding cylinder by an eccentric block. The pneumatic hammer heads and outside sliding cylinders (according to the desired number) are arranged in one, two or more lines and the whole of the eccentrics are carried on shafts at right angles to and in line with the vertical axis of the pneumatic hammer heads and sliding cylinders, so that, a most compact and simple arrangement is obtained.

In order to fully set forth our invention we shall now describe the most suitable construction of mechanism known to us for the purpose. We also indicate one driving arrangement, by which a beetling machine with two beams and with beetles of our type may be driven, without in any way wishing to limit ourselves in respect to any particular way of driving such beetle heads.

The attached drawings will enable the following and more detailed description to be readily understood.

In the said drawings: Figure 1 is a vertical section through one beetle head made according to our invention and clearly illustrates the working. Fig. 2 shows a front view of a portion of a beetling machine fitted with beetles of our type, the figure partly indicating one driving arrangement by which the line of hammers for either beam may be brought into or put out of use as may be necessary. Fig. 3 is a plan showing an arrangement for driving two lines of beetle heads each line being driven together or independently as required.

In a beetling machine preferably having two beams such as 1 on which the cloth to be beetled is wound and which beams run longitudinally down each side, we use two longitudinal girders or beams 2 to support the pneumatic heads. To the longitudinal girders or beams 2, we apply the complete pneumatic heads A. These are closely pitched apart and each of such consists of a fixed

2

sleeve or cylinder 3 which cylinder 3 is bolted to the girder or beam and so held in place. Each cylinder 3 is prepared with an air channel 3^a and fitted with a slidable hammer 4 to which a beetling block 5 is fixed in suitable manner. A back pressure or other valve 6 is fitted with respect to the fixed sleeve or cylinder 3 and such may be a spring pressed ball valve 6. Fitting around the fixed sleeve or cylinder 3, already named, is an outside sliding cylinder 7 which is moved up and down and is guided by the fixed sleeve or cylinder 3. On the downward movement of said outside sliding cylinder, air is drawn in past the back-pressure valve 6, down the air channel 3^a and the outside sliding cylinder 7 is charged with air throughout its entire downward stroke. The slidable hammer 4 carrying the block 5 also falls simultaneously due to gravity and air suction. Upon the return movement of said outside sliding cylinder the air or back pressure valve 6 closes automatically and the air is compressed, the hammer actuated, and the blow from the beetle block delivered.

The outside sliding cylinder 7 has preferably formed therewith an elongated slot or stirrup 8, or is otherwise fashioned to suit the longitudinal shaft 9, and, on this shaft, and in the slot or stirrup is fixed an eccentric 10 by means of a set screw 10^a. In the preferred arrangement which is illustrated, a separate eccentric block 10 is fitted in respect of each outside sliding cylinder 7 (see Fig. 2) each such eccentric engaging the top and bottom of the slot or stirrup 8 or parts attached thereto to effect the desired up and down movement. Such eccentrics can be driven at a high speed so that the sliding cylinders reciprocate smoothly and without knock due to the eccentric peripheries being constantly in touch with the top and bottom faces of the slots or stirrups 8 at all positions in the revolution.

With the construction above indicated, the two shafts 9, 9 drive the two lines of pneumatic heads and thus all the mechanism incidental to driving is as compact as possible. The shafts 9 are supported at close intervals by suitable self-oiling or other pedestals carried on the bed-plates 21.

In the system of driving shown, in respect of the two shafts 9, 9 the main shaft 11 drives by a strap or otherwise the pulley 12 and consequently the shaft 9^a is rotated. On this shaft or on a clutch boss a chain wheel 13 is fixed which, through a chain 14 (preferably a silent chain) drives the chain wheel 15 on the shaft 9^b. Clutches 16, 17, and actuating gear therefor, are fitted so that either actuating shaft 9, 9 can be actuated or stopped at will. The driving arrangements for the sliding cylinders may be greatly varied as is obvious, the mechanism

illustrated merely indicating one plan and being by way of example.

We may fit guards such as 18 or we may incase the parts below the girders or beams 2 so as to keep said parts clear of dirt, fluff, or such like, and to prevent oil or grease being thrown up onto the beetled goods. Also, we may, instead of arranging the pneumatic heads vertically, dispose some or all of the heads obliquely but so that the center line of such beetle heads if continued would strike the center line of the beam.

The up and down movement of each outside sliding cylinder may be brought about by any other mechanical actuating device or gear other than by eccentrics or cams as is obvious, and we wish to reserve the right in respect of equivalent devices for effecting the mere reciprocation of the outside sliding cylinder.

We may combine a cushioning device and also means to put any back-pressure valve and consequently beetle head out of action, as known. The drawings illustrate a form of pivoted lever 19 for this latter purpose, the lever being capable of occupying either of two positions in one of which positions as shown in full lines the ball valve 6 is pushed off its seat against the action of the spring thereby stopping the hammer. In the other position the spring closes the ball valve 6 to back pressure. The part marked 20 is a screwed plug or air cushion plug having a small channel 20^a by the covering of which a small quantity of air is trapped on the descent of the slidable hammer plunger 4 (enlarged at 4^a) such parts serving as a cushioning device.

The eccentrics 10 may be set angularly at 90 degrees successively in advance one to the other, as indicated in Fig. 2, or otherwise as convenient.

We declare that what we claim is:

1. In a pneumatic beetling machine a lower movable cylinder, a fixed cylinder, a sliding hammer support inside said fixed cylinder, a hammer on said support to act against a beam the movable cylinder charging the fixed cylinder during its downward stroke and actuating the sliding hammer support on its return stroke to drive the hammer upward to the beam, the sliding hammer support falling by gravity assisted by air suction as set forth.

2. In a pneumatic beetling machine a fixed cylinder, a sliding hammer support mounted therein, a hammer on said support, and an outside movable cylinder sliding on said fixed cylinder, a stirrup device on said outside movable cylinder, an eccentric engaging said stirrup and a shaft for the eccentric said eccentric being in constant contact with the stirrup at all positions during revolution as described.

3. In a pneumatic beetling machine a fixed

cylinder, a sliding hammer support fitted therein, a hammer on said support an air valve device on the fixed cylinder, an outside movable cylinder around the fixed cylinder, 5 a stirrup on the outside movable cylinder and an eccentric engaging said stirrup and a shaft to support the eccentric, means to drive said shaft, the sliding hammer support falling due to gravity and air suction 10 and being actuated to strike the blow on the ascent of the outside movable cylinder as described.

4. A pneumatic beetling device comprising an over-head cloth beam, a fixed cylinder, an 15 air valve carried thereby, a sliding support therein, a hammer on said support, an outside movable cylinder, a stirrup connected thereto, an eccentric engaging the stirrup, 20 and a shaft carrying said eccentric, all arranged below the cloth beam, and means to drive the shaft carrying the eccentric.

5. A pneumatic beetling machine comprising a number of beetling heads with over-head cloth beam, each beetling head comprising a fixed cylinder, supporting means therefor, a sliding support in each cylinder, 25 a hammer on each support, an outside mov-

able cylinder for each head, an attached stirrup for each movable cylinder, eccentrics for each stirrup differently disposed angularly, a shaft supporting the eccentrics, means to drive the shaft and means to stop 30 said shaft as described.

6. A pneumatic beetling machine comprising a number of beetling heads and having 35 an over-head cloth beam, a fixed cylinder in each head, means to sustain same, an air valve on each cylinder, a sliding support in each fixed cylinder, a hammer on each support, an outside movable cylinder for each 40 head, a stirrup attached thereto, an eccentric for each stirrup, a shaft supporting the eccentrics, means to drive the shaft, and clutch mechanism to arrest or start a line of 45 beetling heads as described.

In testimony whereof we have signed our names to this specification in the presence of two subscribing witnesses.

THOMAS OWEN ARNFIELD.
WILLIAM BOOTH.
